SUPPORT FOR FLEXIBLE CONDUITS ON
RAILWAY CARSEmil Stenzel and John J. Yindrock, Chicago, Ill.,
assignors to Vapor Car Heating Company, Inc.,
Chicago, Ill., a corporation of New York

Application April 20, 1942, Serial No. 439,716

3 Claims. (Cl. 248—53)

This invention relates to certain new and useful improvements in a support for a flexible conduit on a railway car. As is well understood, the adjacent cars of the railway train are provided with couplers which are detachably connected together so that the push or pull from one car may be transmitted to the next adjacent car. On certain types of cars there are similar fluid-transmitting pipes on each car which are provided with flexible connections at their ends adapted to be connected together so that the cars may follow curves without interfering with the continuous transmission of fluids from one car to the next. For example, there is a main steam train-pipe on each car, these train pipes being flexibly connected by suitable conduit sections. In a similar manner, compressed air pipe lines are connected at the adjacent car ends.

These flexible conduit sections are suitably suspended at the relatively fixed ends of the car pipes, but additional supporting means are often provided for intermediate sections of these flexible conduits, particularly when these flexible conduits are quite heavy. The flexible extensions of steam pipes are now often made of relatively rigid metallic or partially metallic sections articulated together by suitable universal joints. These sections are of considerable size and weight and flexible suspending means are often provided between certain of these sections and superposed portions of the car or the car-coupling means. The present invention relates to a new and improved form of such supporting means.

In the present example, each car is provided with a coupler at the end of a draw-bar swinging about a pivotal connection beneath the car so that the car coupler has a limited arcuate movement between the adjacent end portions of the cars, means being provided for detachably connecting the couplers so that a substantially continuous draw-bar is provided connecting the two cars. Flexible link supports suspend the free end portions of the flexible steam conduits (which are provided at their free ends with suitable coupling members) beneath the larger and stronger car-couplers hereinabove described. Additional link supports are provided for intermediate sections of the flexible conduits, these additional supports being suspended at their upper ends on trackways provided beneath relatively fixed portions of the car bodies adjacent to but not sharing the lateral swinging movement of the car couplers. Since the intermediate sections of the flexible conduit structures must move both longitudinally and laterally in a substantially horizontal plane with

relation to the cars themselves, when the cars are passing around a curve, the trackways for these intermediate link supports are so positioned as to permit the links to maintain a substantially vertical position as the flexible conduit sections move bodily in a longitudinal direction. This properly distributes the tension and reduces wear in the flexible conduits and improves the easy and flexible operation of these heavy parts.

10 The principal object of this invention is to provide an improved form of supporting means for a flexible conduit section as briefly described hereinabove and disclosed more in detail in the specifications which follow.

15 Other objects and advantages of this invention will be more apparent from the following detailed description of one approved form of this apparatus.

In the accompanying drawings:

Fig. 1 is a diagrammatic plan view of the adjacent end portions of a pair of connected cars, showing the connected car couplers, and the connected flexible conduit sections on the adjacent cars.

20 Fig. 2 is a side elevation of one of the flexible conduits and associated parts.

Fig. 3 is a plan view of one of the conduits, with a portion of one of the car-couplers shown in dotted lines, this view being taken substantially

30 on the line 3—3 of Fig. 2.

Fig. 4 is an elevation of the improved supporting link and a portion of the trackway therefor.

Fig. 5 is a side elevation of this link taken at right angles to Fig. 4.

35 In Fig. 1, a pair of similar cars A and B are indicated in outline while passing around a curve, the cars being connected by the coupler bars C and C' provided with connected coupler heads D and D'. The couplers are pivotally connected on

40 vertical axes beneath the respective end portions of the cars substantially at the points a and a' so that the coupler bars form substantially straight line extensions of one another and the connected coupler heads will swing from one side to the other of the center line of the train as the adjacent cars pass around a curve.

On each car there is a similar steam train-line 1 which extends from end to end of the car and from which the heating equipment on the car is supplied. Usually this train line receives its steam from the source at the locomotive. Each end of this pipe 1 terminates in an end train pipe valve 2 which is suitably supported by a bracket member 3 on the car. The valve at the end of the train will be closed, but the train pipes on any

adjacent cars of the train will be connected by flexible conduits E and E' and the valves 2 will be opened to permit a continuous circulation of steam throughout the length of the train.

Each of the conduit members (for example E) comprises an inner section 4 which extends inwardly and downwardly toward the center line of the car and which is suspended at 5 beneath the valve 2 so as to connect with the steam line. The other end of pipe section 4 is adapted to swing in a substantially horizontal plane about an arc extending vertically through the end valve 2. A second pipe section 6 extends substantially horizontally parallel to the center line of the car and is provided with a head portion 7 at its inner end which extends upwardly at 8 and is pivotally connected with the downturned end 9 of the first section 4. The outer end of the pipe section 6 carries a coupler head 10 adapted to mate with a similar head 10' on the other conduit member E' whereby the steam connections between the adjacent cars are completed. A spring supporting member 11, of known type, is connected at its lower end to a collar 12 on the conduit 6, and is connected at its upper end by a hook member 13 with a lug 14 projecting downwardly from the car coupler head D. The connected conduits 6 will normally extend longitudinally of the train substantially beneath the car couplers and parallel thereto, but when rounding a curve the couplers D will usually swing somewhat to one side or the other of the conduit sections 6, as indicated in Fig. 1. The swinging link members 11 permit these relative movements while at the same time providing suitable supports for these end portions of the conduit members.

A second spring supporting member, indicated generally at G is provided for guiding and suspending the intermediate sections of the conduit E. The intermediate portion of the draw-bar C, directly back of the coupler head D and beneath the end of the car, is supported from a suitable coupler carrier F, fixedly carried by the end portion of the car. This carrier F extends beneath the coupler bar and supports the outwardly projecting bar and head to slide laterally as the car passes around a curve. A track-way or trolley-rod 15 is supported at its ends in any suitable manner beneath the carrier F so as to extend beneath this carrier at a slight angle to the longitudinal center line of the car in a direction tangent to or substantially parallel to a tangent to the arc of swinging movement of the connected ends of the conduit sections 4 and 6. On the upper face of the head 7 at this inner end of the section 6 is secured a vertically extending plate 16 provided with a series of similar openings 17 sloping upwardly substantially in the plane of the section 4. A connecting link 18 has its upper hooked end 19 engaged with the lower hooked end of a spring link 20, while the lower hooked end 21 of link 18 is engaged in one of the openings 17. The upper end of spring link 20 is engaged with the downwardly looped

central portion of the shackle 22, the upper arms of which are connected by a pin 23 carrying the roller or trolley 24 which slides along the guide-rod 15. The supporting link G thus serves to support the connected end portions of the conduit sections 4 and 6 while permitting these pivotally connected conduit sections to swing beneath the end portions of the car substantially around the vertical axis of the end train-pipe valve 2. The outwardly extending end of section 4 swings in a substantially horizontal plane about this axis, whereas the section 6 moves bodily lengthwise substantially in the direction of the longitudinal center line of the car. The trolley 24 and supporting rod 15 permit the supporting mechanism G to move with the conduit sections so that the link will remain substantially vertical. The proper tension and inclination of this link mechanism G can be adjusted by changing the connecting link 18 from one to another of the series of openings 17 in plate 16.

The supporting link mechanism G serves to intermediately support the flexible conduit members E at all times, the tension being so distributed that unnecessary wear on the pivotally connected conduit sections will be avoided and the swinging and rotary movements of the parts will be facilitated.

We claim:

- 30 1. Supporting means for a section of a movable conduit, comprising a substantially vertically disposed link comprising an extensible spring, a plate fixed to the conduit, means for adjustably securing the lower end of the link to the plate, a trackway supported above and substantially in line with the path of movement of the conduit section, and means freely movable along the trackway and supporting the upper end of the link.
- 35 2. Supporting means for a section of a movable conduit, comprising a substantially vertically disposed link comprising an extensible spring, a plate fixed to the conduit, means for adjustably securing the lower end of the link to the plate comprising a plurality of openings in the plate, and a hook selectively engaging one of the openings, a trackway supported above and substantially in line with the path of movement of the conduit section, and means freely movable along the trackway and supporting the upper end of the link.
- 40 3. Supporting means for a section of a movable conduit, comprising a substantially vertically disposed link comprising an extensible spring, a plate fixed to the conduit, means for adjustably securing the lower end of the link to the plate, a trackway supported above and substantially in line with the path of movement of the conduit section, and a roller suspending the upper end of the link and movable along the trackway.
